(57) **CLAIM**

The ornamental design for a cap for a container, as shown and described.

DESCRIPTION

FIG. 1 is an isometric view of a cap for a container showing my new design;

FIG. 2 is another isometric view thereof;

FIG. 3 a side view thereof;

FIG. 4 is another side view thereof;

FIG. 5 is another side view thereof;

FIG. 6 is another side view thereof;

FIG. 7 is a top view thereof; and,

FIG. 8 is a bottom view thereof.

The broken line showing of portions of the cap interior depicts environment and forms no part of the claim.

1 Claim, 4 Drawing Sheets
